UNITED STATES PATENT OFFICE.

WILLIAM T. TAGGART, OF PLAINFIELD, NEW JERSEY, ASSIGNOR, BY DIRECT AND MESNE ASSIGNMENTS, OF ONE-HALF TO IRA W. COLE, OF PLAINFIELD, AND ONE-HALF TO LEWIS A. STRAIT, OF ROCKAWAY, NEW JERSEY.

FAUCET.

1,200,268.

Specification of Letters Patent. Patented Oct. 3, 1916.

Application filed March 27, 1916. Serial No. 86,972.

To all whom it may concern:

Be it known that I, WILLIAM T. TAGGART, a citizen of the United States, residing at Plainfield, in the county of Union and State 5 of New Jersey, have invented certain new and useful Improvements in Faucets; and I do declare the following to be a full, clear, and exact description of the invention, such as will enable others skilled in the art to 10 which it appertains to make and use the same.

This invention relates to improvements in faucets and more particularly to faucets so constructed as to enable the main valve to 15 be removed without necessitating shutting off the water.

The object of the invention is to provide a faucet of this character so constructed that ready access may be had to the main 20 valve without either removing the faucet or cutting off the water supply in the main pipe.

With this and other objects in view, the invention consists of certain novel features 25 of construction, and the combination and arrangement of parts as will be more fully described and claimed.

In the accompanying drawings:—Figure 1 represents a vertical longitudinal section 30 of a faucet constructed in accordance with this invention with the main valve shown closed and the auxiliary valve open; Fig. 2 is a similar view with parts broken off showing the main valve open and the auxiliary valve partially closed; Fig. 3 represents a side elevation partly in section with the main valve shown removed and the auxiliary valve closed.

In the embodiment illustrated a faucet is 40 shown, the body or shell 1 of which is preferably cast in one piece and is provided with the usual inlet 2 and an outlet 3, the latter being in the form of a downturned spout as is usual in faucets of this character, and 45 the inner ends of said inlet and outlet being offset vertically from each other with a chamber 4 formed between them. This chamber 4 has a concave or rounded bottom 5 and is provided at its upper end or at a point diametrically opposite said bottom 50 with an internally threaded opening 6 which communicates with the outlet 3 and with a tubular extension 7 which projects laterally,

upward from the shell 1 in alinement with the opening 6 of said chamber. This tubular extension 7 is internally threaded to receive a threaded enlargement 8 carried by the shank or stem 9 of the main valve 10. The valve shank or stem 9 is provided at its outer end with an operating wheel or 60 handle 11 which may be of any suitable or desired construction. The extension 7 is closed at its outer end by a cap 12 having a central aperture 13 through which the stem 9 of the valve 10 passes and is adapted 65 to slide freely therein. This extension 7 also has an auxiliary closure formed within the cap 13 and shown in the form of an apertured metal disk 14 which seats in the outer end of the extension 7 and has ar- 70 ranged thereover a coöperating locking member in the form of a disk 15 preferably made of hard rubber which is carried by the cap 12 and between which and said cap 75 is arranged a packing 16 to insure a water-tight connection where the valve stem 9 passes through the cap.

The valve 10 has a seat 17 at its inner end in which is mounted a hard rubber disk 18 which is designed to seat when closed on an 80 annular shoulder 19 formed on the outer end of an inverted hollow truncated cone-shaped valve seat 20 mounted in the opening 6 of the chamber 4. This tubular or sleeve-like valve seat 20 is externally 85 threaded for engagement with the threaded opening 6 and the inner tapered end thereof is extended into the chamber 4, the outer face of said projecting end being ground to form a seat for an auxiliary valve 21 90 which is designed to fit over said tapered end and close the outlet from the chamber 4 under conditions to be described. This sleeve 20 may be provided with any suitable means for inserting and removing it, an 95 opening such as 20° being here shown for the insertion of an actuating tool.

A stem or rod 22 is carried by the valve 10, being here shown having threaded engagement therewith and projects through 100 the tubular valve seat 20 to a point some distance below the inner end thereof, being designed to engage the cup-shaped auxiliary valve 21 and hold said valve normally out of engagement with the seat 20, as is shown 105 clearly in Fig. 1.

Guide ribs 23 are formed on the inner face of the side walls of the chamber 4 between which the auxiliary valve 21 is designed to operate and be guided thereby in its opening and closing movements and held against lateral displacement. These guide ribs 23 which are cast integrally with the casing or shell 1 are provided at their ends with laterally extending stops in the form of shoulders 24 for limiting the inward or opening movement of the auxiliary valve 21, as is shown clearly in Fig. 1.

At the entrance of the inlet into the chamber 4 is formed a transversely extending lip 25, the free end of which terminates at a point spaced from the opposed wall of the inlet 2 from which it projects, thereby reducing the size of the inlet where it enters the chamber and serving to direct the entering fluid downwardly against the rounded chamber bottom 5 of the chamber 4 and against the lower face of the cup-shaped valve 21 which is positioned substantially in alinement with the lower edge of the deflecting lip 25 so that the force of the water is exerted against said valve and when the main valve is removed, will operate to quickly seat the valve against the tapered end of the valve seat 20. The entering fluid impinges against this rounded chamber bottom and is thereby directed upwardly in a direction sufficiently at right angles to the direction of its entrance whereby the force of the inflowing current is directed against the lower face of the auxiliary valve 21 and exerts its pressure to force said valve toward its seat so that when the stem or rod 22 is moved away from said valve it will closely engage the seat formed at the inner end of the member 20 and securely cut off the water outlet from the faucet. As shown, this cup-shaped auxiliary valve 21 is in the form of a ground valve for coöperation with the ground seat formed at the inner end of the member 20, and the outer face of said valve is substantially inverted cone-shaped so that the pressure of the inflowing fluid will be discharged over the entire area of the outer face of said valve and thus hold it firmly seated when the rod 22 is removed from its engagement therewith.

From the above description, the operation of this improved valve will be obvious, it being understood that when the main valve 10 is moved inwardly into closed position as shown in Fig. 1, the disk 18 carried thereby will be seated on the upstanding annular shoulder 19 formed on the tubular valve seat 20, and that when so engaged, the rod or stem 22 will engage the cup-shaped auxiliary valve 21 and hold it in open inoperative position against the stops 24 formed on the guide ribs 23, as is shown clearly in Fig. 1. When it is desired to open the faucet for permitting the passage

therethrough of the fluid to be discharged, the valve 10 is opened by turning the valve stem 9 in the proper direction to move said valve outwardly into the position shown in Fig. 2, whereby communication between the inlet 2 and the outlet 3 will be effected through the tubular sleeve 20, the rod 22 being of a length sufficient to hold the auxiliary valve open when the main valve is in this position and thus prevent interference of said auxiliary valve with the discharge of the fluid through the faucet.

When for any reason, it is desired to remove the main valve 10 or to obtain access to its seat for repairing or other purposes, the operating handle 11 is turned until the threaded enlargement 8 is entirely disengaged from the threaded extension 7, whereby the valve is entirely disconnected from the faucet, and immediately the stem 22 passes out of its engagement with the auxiliary valve 21, the force of the water pressure in the chamber 4 will cause said valve to seat firmly against the inner end of the tubular member 20, as shown in Fig. 3, thereby cutting off the outflow of the fluid through the faucet. After the valve 10 has been repaired or a new one substituted, it is replaced in the faucet by reversing the operation above described, whereby the stem 22 will again be engaged with the auxiliary valve 21 to force it away from its seat and prevent it from closing or cutting off the outflow through the faucet, the outflow then being controlled by the main valve 10.

I claim as my invention:—

The combination of a faucet having an inlet and an outlet offset vertically from each other with a chamber between them, said chamber having a concave bottom and provided at a point diametrically opposite said bottom with an internally threaded opening communicating with said outlet, an internally threaded tubular extension projecting upward in alinement with the opening in said chamber, a hollow inverted truncated cone-shaped valve seat mounted in said chamber opening and provided with an annular shoulder at its upper end, the tapered end of said seat extending into said chamber and ground on its outer face to form a seat, vertical guide ribs on the inner face of the side walls of said chamber provided at their lower ends with laterally extending stops, a cup-shaped valve slidable between said ribs and adapted to fit over the tapered end of said valve seat when closed, a transversely extending lip depending from the upper wall of the inlet to the chamber, a main valve movable toward and away from the seat in said outlet and having threaded engagement with said extension, a rod carried by said main valve and extending into and normally engaging said cup-shaped valve for holding it away from

its seat, said rod being of a length sufficient to hold said cup-shaped valve with its outer face alining with the free edge of said lip to position it to receive the force of the inflowing water, whereby said valve is quickly seated on the removal of the main valve.

In testimony whereof I have hereunto set my hand in presence of two subscribing witnesses.

WILLIAM T. TAGGART.
